UNITED STATES PATENT OFFICE

GEORGE H. SOMMERFIELD, OF CLEVELAND, OHIO

CLEANING DEVICE

Application filed March 16, 1929. Serial No. 347,593.

This invention relates to improvements in devices for cleaning windows, woodwork and the like and has for an object to provide a reservoir, a moistener and a squeegee combined in a compact unitary assembly in which the moistener and the squeegee are disposed relatively to the reservoir and to one another for most convenient use.

Other purposes are to provide a reservoir of such construction that it may be produced cheaply, easily and quickly from sheet material and which, in its completed form, will be stiff and sturdy even though the material from which it is formed is relatively thin; to provide means for securing the squeegee to the reservoir in such manner that it is maintained firmly connected with the reservoir yet is capable of quick, convenient detachment therefrom; to provide simple, convenient means for operatively mounting the moistener on the reservoir, and, in general, to provide a complete device of the type mentioned which is simple in construction, inexpensive to produce, strong, durable and thoroughly reliable and efficient in use.

With the foregoing and other purposes in view, the invention consists in the novel features of construction, combination and arrangement of parts as will be hereinafter more fully described, illustrated in the accompanying drawings and defined in the appended claims.

In the drawings, wherein like characters of reference denote corresponding parts in the different views:—

Fig. 1 is a perspective view of a cleaning device constructed in accordance with this invention.

Fig. 2 is a transverse section taken centrally through the device.

Fig. 3 is a detail section on the line 3-3 of Figure 1; and

Fig. 4 is a fragmentary section on the line 4-4 of Fig. 2.

Referring now to the drawings in detail, it will be observed that the present device comprises a reservoir A, a moistener B and a squeegee C.

Reservoir A, which may be formed from

any suitable material into any desired size and shape, preferably is formed from sheet metal and is of somewhat elongated form and of substantially semi-cylindrical cross-section. It consists of a body portion 10 and end closures 11, 11, body portion 10 preferably being pressed from a single blank of material to include, in cross-section, a flat lower side 12, a curved upper side 13, and a pair of spaced parallel lips 14, 14 constituting by the longitudinal marginal edge portions of said body, extending outwardly from one side of portion 13 adjacent to the flat lower side 12 thereof.

The marginal end portions of body 10 are turned outwardly to provide flange 15, and the end closures 11, 11 which are of cup-like or dished form so as to fit into body 10 thereby to reinforce and stiffen same, have their marginal portions 16 crimped over said flanges whereby the end closures are rigidly secured to the body in water-tight relation thereto.

Moistener B which may be formed from any suitable absorbent material such as felt, sponge rubber or the like, preferably is somewhat longer than reservoir A, of such thickness as to fit when compressed between the lips 14, 14 and of a width to extend any suitable distance outwardly beyond the free edges of said lips when the inner edge thereof is engaged against the adjacent edges of the end closures 11, 11. Said moistener is adapted to be detachably secured between the lips 14, 14 in the relation stated in any suitable or desired manner, for example, as shown, by means of a series of bolts 17 engaged through aligned openings in the lips and through the moistener.

By reason of the moistener being longer than the reservoir A the projecting end portions 18 of the moistener provide guards preventing end portions of the reservoir from contacting with and perhaps marring surfaces adjacent to a surface being cleaned by the device, while by reason of the bolts 17 a moistener may readily be reversed or replaced whenever occasion demands.

Reservoir A is adapted to contain water or other cleaning liquid and since the inner

face of moistener B is exposed to water or other liquid contained within the reservoir it is manifest that due to capillary attraction the moistener will be maintained wet so long as sufficient liquid remains in the reservoir to wet the inner face of the moistener. A filling opening 19 is formed in the reservoir at any desired point and this opening may be maintained normally closed by any suitable form of cap or plug 3 preferably a cork or rubber stopper indicated at 20. The said stopper 20 is provided with a hollow plug 20^a, slidably in a central opening in the stopper so that the vent opening 20^b therein may be opened and closed by the shifting of the plug. The said plug is preferably flared at its inner end as indicated at 20^c and its outer end is formed with a head or finger engaging nob 20^d. The purpose of the 20 vented plug 20^a is to permit the water holding chamber to be vented to the atmosphere and permit free flow of water to the moistener B. When the plug is pushed in the stopper to cover the vent opening 20^b water 25 cannot, of course, leak out of the chamber and likewise the chamber is cut off from the atmosphere. On the other hand when the vent is uncovered water may freely flow through the moistener B.

30 Squeegee C which may consist of an elongated strip of rubber or other pliable material 21 stiffened along its inner edge by a strip of metal 22 of substantially U-shaped, outwardly tapering cross-section, is adapted to be secured to the reservoir body at any suitable point along the side thereof opposite to the moistener B, and to this end an elongated channel member 23 having the same or approximately the same cross-section as the reinforcing strip 22, is riveted, soldered or otherwise rigidly secured to the body 10 to receive the reinforced inner edge of the squeegee. An outwardly bowed leaf spring 24 is disposed within member 23 and 35 when the squeegee is engaged within said member said spring functions to urge same outward with consequent wedging engagement between the outwardly tapering sides of the strip 22 and the similarly tapering sides of the channel member 23, whereby the squeegee is maintained firmly connected normally with the reservoir. As is apparent the squeegee is readily engageable with and disengageable from member 23 by longitudinal sliding movement thereof with respect to said member.

Secured by means of rivets, solder or in other suitable manner to the flat lower face of body 10 is a threaded member 25 over or into which is adapted to be threaded a handle or handle socket 26 for manipulating the device.

In the use of the device moistener B is adapted to be employed initially to wet and to some extent clean a surface such as a window, while squeegee C is adapted subsequently to be employed to wipe the surface clean, the relative arrangement of the elements B and C as shown and described enabling the respective operations to be performed conveniently without necessitating any material angular alteration of the position of the handle 25 with respect to the surface being cleaned, and the shape of reservoir A and the disposition of the squeegee 75 adjacent to the flat lower face thereof assuring that the moistener will remain damp or wet so long as substantially any liquid remains in the reservoir.

From the foregoing description considered in connection with the accompanying drawings, it is believed that the construction and the advantages of the present device will be clearly understood. It is desired to point out, however, that the structure shown may be modified in various respects within the spirit and scope of the invention as defined in the appended claims.

I claim:

1. A device of the character described comprising a body member, a squeegee having converging side portions, means for connecting said squeegee with said body member comprising a channel member carried by the body member and having converging sides to receive therebetween the converging side portions of the squeegee, and a leaf spring within said channel member adapted to exert pressure against the squeegee to maintain the converging side portions thereof in engagement with the converging sides of said channel member.

2. In a device of the character described, a reservoir, a porous moistener carried by said reservoir adapted to be supplied with liquid therefrom, said reservoir having a filling opening, a stopper for said opening, and a tube slidably mounted in said stopper, said tube being closed at its outer end, open at its inner end, and provided with a lateral opening adapted to be covered and uncovered by sliding movement of said tube relative to the stopper to admit or deny the entrance of air into the reservoir.

3. In a device of the character described, a supporting body, a member carried by said supporting body having a channel of less width at the outer side than at the inner side of the member, a squeegee having a portion of greater width than the least width of said channel disposed within the latter, and spring means urging said squeegee portion in the direction of the portion of least width of said channel to maintain the squeegee in assembly with said channel member.

In testimony whereof I hereunto affix my signature.

GEORGE H. SOMMERFIELD.
